US0D1082001S

(12) **United States Design Patent** (10) **Patent No.:** **US D1,082,001 S**
(45) **Date of Patent:** **** Jul. 1, 2025**

(54) **INCUBATOR**

(71) Applicant: **Dezhou Weiqian Import and Export Co., LTD**, Shandong (CN)

(72) Inventor: **Dehua Meng**, Shandong (CN)

(73) Assignee: **Dezhou Weiqian Import and Export Co., LTD**, Dezhou (CN)

(**) Term: **15 Years**

(21) Appl. No.: **29/913,158**

(22) Filed: **Sep. 27, 2023**

(51) **LOC (15) Cl.** **24-01**

(52) **U.S. Cl.**

USPC **D24/163**

(58) **Field of Classification Search**

USPC D24/163, 107, 164, 185, 186, 217, 231, D24/232, 216, 223, 224, 226, 227, 229; D10/48, 46, 50; D23/334, 332, 356; D9/756, 757, 758

(57) **CLAIM**

The ornamental design for an incubator, as shown and described.

DESCRIPTION

FIG. 1 is a top, rear, left side perspective view of an incubator showing my new design;

FIG. 2 is a bottom, front, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of an incubator which is decomposed state.
The broken lines show features of the incubator that form no part of the claimed design.

1 Claim, 9 Drawing Sheets
